UNITED STATES PATENT OFFICE

JOHN FERDINAND FERM, OF MIDLAND, PENNSYLVANIA, ASSIGNOR TO PITTSBURGH CRUCIBLE STEEL COMPANY, OF PITTSBURGH, PENNSYLVANIA, A CORPORATION OF PENNSYLVANIA

DESIGN FOR A STANDARD FOR STREET LIGHTS OR OTHER ARTICLES

Application filed July 19, 1932. Serial No. 44,378. Term of patent 14 years.

To all whom it may concern:

Be it known that I, JOHN FERDINAND FERM, a citizen of the United States, residing at Midland, in the county of Beaver and State of Pennsylvania, have invented a new, original, and ornamental Design for a Standard for Street Lights or Other Articles, of which the following is a specification, reference being had to the accompanying drawing, forming part thereof.

Figure 1 is a side view, and Figure 2 is a section on line 2—2 of Figure 1, showing my new design.

I claim:

The ornamental design for a standard for street lights or other articles, as shown.

JOHN FERDINAND FERM.
